UNITED STATES PATENT OFFICE

162,081

ICEBOX DISH

Lee H. Precourt, Whittier, Calif., assignor, by direct and mesne assignments, to Coast Fishing Company, Los Angeles County, Calif., a corporation of California

Application December 19, 1949, Serial No. 6,712

Term of patent 14 years

(Cl. D44—1)

To all whom it may concern:

Be it known that I, Lee H. Precourt, a citizen of the United States and resident of the city of Whittier, county of Los Angeles, State of California, have invented a new, original, and ornamental Design for an Icebox Dish, of which the following is a specification, reference being had to the accompanying drawing, forming a part hereof, in which:

Fig. 1 is a top plan view of an icebox dish, showing my new design;

Fig. 2 is a side elevational view;

Fig. 3 is a bottom plan view; and

Fig. 4 is a transverse vertical sectional view thereof.

I claim:

The ornamental design for an icebox dish, substantially as shown.

LEE H. PRECOURT.
